The ornamental design for a flying disk, as shown and described.

DESCRIPTION

FIG. 1 is a prospective view of a flying disk showing my new design;

FIG. 2 is a top plan view thereof; and

FIG. 3 is a bottom plan view thereof; and,

FIG. 4 is a front elevational view thereof, the rear elevational view and the left and right side elevational views being the same.

Fig. 1.

Fig. 2.

Fig. 4.

Fig. 3.
